UNITED STATES PATENT OFFICE.

WILLIAM WORTH BURSON, OF CHICAGO, ILLINOIS.

STRAIGHT-KNITTING MACHINE.

No. 892,933.

Specification of Letters Patent.

Patented July 7, 1908.

Original application filed June 7, 1897, Serial No. 639,677. Divided and this application filed February 4, 1905.
Serial No. 244,077.*To all whom it may concern:*

Be it known that I, WILLIAM WORTH BURSON, a citizen of the United States, residing at Chicago, in the county of Cook, State of Illinois, have invented a certain new and useful Improvement in Straight - Knitting Machines, of which the following is a specification, reference being had therein to the accompanying drawings.

10 My invention relates to knitting machines of the class in which there are employed in a given machine two straight rows of needles, such machines being known as parallel row machines.

15 The objects of my invention are, in general, first, to provide means to cause the yarn-carrier to move in proper relation with respect to the moving needle-actuating cams; second, to provide means for enabling a tubular fabric to be knit with an additional or splice yarn introduced into a longitudinal portion of the same; third, to provide means for crossing said splice-yarn from one row of needles to the other at an intermediate point 20 of the tubular fabric which is in course of being knit, so as to avoid waste of said splice-yarn; and fourth, to provide means to cut the portion of splice-yarn which extends or crosses from one row of needles to the other, 25 as the knitting progresses.

An embodiment of the various features of the invention is illustrated in the accompanying drawings, in which latter,—

Figure 1 is a top view of certain portions of a parallel-row knitting machine containing the said embodiment. Fig. 2 is a view in vertical section on the plane indicated by the dotted line 2 2, Fig. 1. Fig. 3 shows a view of certain of the parts in section on the same line, the presser-hooks being somewhat farther apart than in Fig. 2. Fig. 4 shows a portion of the length of the presser - hook cam-bar. Fig. 5 is a view in elevation on a somewhat larger scale, showing chiefly the 30 yarn-carrier, the knife for severing the portion of splice yarn which crosses from one row of needles to the other, and certain of the parts which are concerned in operating the yarn-carrier, the splice yarn guide, and 35 said knife, the said devices being viewed from the side that is farthest from the operator. Fig. 6 is a detail view in section on the line 6 6 of Fig. 5. Fig. 7 shows in elevation certain of the parts adjacent one end of the 40 machine, comprising one of the switches by

which the needle-operating cams are placed in and out of position for engaging with the needles and adjacent parts. Fig. 8 shows the parts of Fig. 7 in plan, and in connection therewith the eccentric block G⁴ pertaining 45 to the corresponding needle-operating cam, and portions of the carrier-arm G³ of said cam, the plate B⁴ being removed. Fig. 9 shows in elevation the switch and adjacent parts which are employed at the opposite end 50 of the same side of the machine, with block G⁴ represented as occupying a position slightly to the left of the said switch. Fig. 10 shows the block G⁴ at the right hand side of the switch, and as having just engaged the 55 point of the switch in the movement of the needle-operating cams from right to left. In dotted lines this figure shows the inoperative position into which the switch may be raised when it is desired to prevent engagement of 60 the block and switch with each other. Fig. 11 shows the same parts as Fig. 10, but represents them in the position which they occupy when block G⁴ has been almost completely turned by the engagement of the 65 switch H therewith. Fig. 12 is a detail view showing one of the levers h³ and certain parts connected therewith.

Similar letters refer to similar parts throughout the different views.

It is not considered necessary to illustrate more of the knitting mechanism than is required to show the improvements and indicate the relations and mode of operation thereof. The knitting mechanism in connection with which the invention is employed may correspond in the main with that shown and described in United States Letters Patent No. 616,600, granted to me December 27, 1898.

Having reference to the drawings,—at A in Fig. 2 is represented portion of a machine-frame, it having its upper surfaces inclined at an angle of about 30° to each other. The opposite needle-beds B B are fastened on 90 these inclined surfaces. To the needle-bed at each side of the machine are fastened the guide-bars B' and B² for the corresponding needle-operating cam-slide G, and also the presser-hook supporting-bed or segment C of such side. The bar B³ which is fastened to the top of the bar B² serves to hold the cam-slide G and presser-hook-cam-bar C³ 100 down in place. The plate B⁴ projects inward beyond the inner edge of the bar B' to 105

95

110

form an upper guide for the block G^4 to which reference presently will be made. The bar C^2 which is fastened on the segment C' at each side of the machine serves to hold the presser-hooks C down in place, and serves also as a support along which one edge of the yarn-carrier T travels in the movements of the latter. The needle-projecting cam G' , Fig. 2, at each side of the machine, is fastened to the carrier-bar G^3 , as shown more particularly in Figs. 1 and 2. The said carrier-bar G^3 is pivotally mounted or hinged upon the cam-slide G at g^2 , Fig. 1. The said cam G' , thus mounted or supported in connection with the cam-slide is adapted to be shifted or adjusted, in a direction perpendicular to the plane of the needle-bed, into and out of position for engagement with the bits or heels of the jacks D which are employed in connection with the needles E . I presently will explain the manner of effecting this shift or adjustment for the purpose of knitting tubular goods, and the means by which the same may be effected automatically. The needle-retracting cams G^2 , one thereof being shown at the right hand side in Fig. 2, are fastened to the cam-slide G in any approved manner. The jack D , needle E , and filler-piece E' , Fig. 2, are combined and operate in manner which will readily be understood. Motion is given to the cam-slides G, G , by the crank X^2 , Fig. 1, through pitman X' , the latter being connected at one end thereof to the said crank-pin, and at the other end thereof to the cross-bar X which is fastened to the ends of the said cam-slides.

Referring first to the means of producing the shift or adjustment of the needle-projecting cams at the two sides of the machine in the order that is required for tubular knitting, the devices for the purpose which I have shown herein are the same as in my application for U. S. patent for knitting machines filed June 7, 1897, Serial No. 639,677, of which the present case is a division. Thus, H, H , are switches which are employed at the opposite ends of each needle-bed, as shown best in Fig. 1. Figs. 7 and 9, taken together, show the opposite ends of one of the needle-beds, and the switches which are located at such ends. As shown best by Figs. 7 to 11, Fig. 3, each switch H is pivoted at h upon the inner edge of one of the bars B' , and has the inclined projection h' adjacent its free or operating end. The free extremity of the switch-arm is curved upwardly, as at h^6 . The switch-arm is furnished with the upright arm or extension h^2 , which last is engaged by the movable controlling arm or lever h^3 . The said arm or lever h^3 is constituted in the present instance of a strip which is attached by one end thereof to the upper surface of the plate B^4 and at its other or free end enters a horizontal notch in the arm or extension h^2 , so that when the arm or

lever is moved vertically it communicates a corresponding movement to the switch. Upon the plate B^4 adjacent each switch is affixed the guard projection h^6 , against the inner side of which the proximate side of the curved part h^5 of the switch takes lateral bearing, thus serving to relieve the pivot h from part of the strain which the operation of the switch tends to transmit to said pivot. The spring h^4 , Figs. 1 and 9, operates with a tendency to hold the controlling arm or lever h^3 depressed, and, when permitted to do so, places and keeps the switch in the operative position thereof in which it is shown by full lines in Figs. 7, 9 and 10. The controlling arm or lever h^3 is engaged and actuated by means of a push-bar H^2 , Figs. 9 and 12, which latter at its upper end is notched to engage with the arm or lever h^3 . When the said push-bar is moved upwardly, which may be effected either by hand or by the action of suitable pattern-devices, it raises the said arm or lever h^3 , and thereby lifts the switch H out of the said operative position into the inoperative position in which it is represented in dotted lines in Fig. 10. Each carrier-arm G^3 has mounted thereon upon a pivot-pin g , Figs. 9, 10 and 11, an eccentric block G^4 . The latter consists, substantially, of a cylindrical part or body, which preferably is flattened slightly on diametrically opposite portions, and is furnished with a flange that is flattened at the opposite sides thereof correspondingly with the said cylindrical part or body, the said flange being somewhat elongated and formed with pointed ends g', g' . The hole which is formed in block G^4 for the reception of the stud g which connects the same pivotally with cam-bar G^3 is eccentrically located with relation to the cylindrical portion or body of the said block. By the reciprocating movements of the cam-slide G the said block, thus pivoted eccentrically to the carrier-arm G^3 which holds the needle projecting cam G' , see Figs. 7 to 11, is caused to travel along the inner edge of the guide-piece B' , beneath the projecting edge-portion of plate B^4 , and between such edge-portion and a lower guide for the block. The said lower guide may be constituted by the upper surface of the adjacent needle-bed, or otherwise if preferred. Successive half-turns of the block will alternately raise the needle-projecting cam into inoperative position above the bits or heels of the jacks, and lower the same into operative position to engage such bits or heels and thus cause the needles to be actuated, as the case may be.

Referring to Figs. 7 and 9, it will be noticed that in Fig. 9, the block G^4 being in the position which permits the needle-projecting cam G' to occupy its operative position, the said cam in the movement thereof along the corresponding needle-bed in the direction from

right to left will act to project the needles of such needle-bed. In such movement, when the leading end of the block G^4 reaches the point h' of switch H , Fig. 7, at the left hand end of the needle-bed, it will engage therewith as in Fig. 10, and as such movement of the cam toward the left continues the said leading end will be tipped upward and the block turned end for end, the turning movement being indicated in Fig. 11. By the new position thus given to the block G^4 the pivot g will be caused to occupy a higher position, and thereby the needle-projecting cam G' will be raised into inoperative position with relation to the heels or bits of the jacks and during the return movement of the knitting-cams, that is to say, in the direction from left to right, the needles of the said needle-bed will not be actuated by such cam. In such return movement the block G^4 will pass under the inclined piece h' of each switch H , thereby lifting the respective switches out of the way and will not be turned. In the succeeding movement of the knitting-cams from right to left the right hand switch will act to communicate a half-revolution to the block G^4 , restoring it to its relative position in Fig. 9, lowering the needle-projecting cam into operative position, so that during such movement the needles of the said needle-bed will be actuated to knit. At the conclusion of the movement the left-hand switch will repeat its action represented by Figs. 10 and 11, raising thereby the needle-projecting cam into inoperative position. While this operation proceeds at one side of the machine, a corresponding operation will be proceeding upon the other. For tubular knitting it will be understood that when the knitting-cam at one side of the machine is depressed into operative position for the stroke in one direction, the knitting-cam at the opposite side of the machine is raised into inoperative position, and vice versa for the stroke in the opposite direction. It will be clear that tubular work may be knit indefinitely without any change of the switches if the blocks G^4 at the opposite sides of the machine are started properly. Changes from tubular knitting to flat knitting, and vice versa, may be occasioned as desired by causing the respective switches to be moved into and out of operative position at the required times, either by hand or by pattern-connections.

The presser-hook cam-bars C^3 C^3 are operated by the cross-bar X , Fig. 1, through the engagement of the latter with lugs or bosses c^{31} c^{31} with which the said cam-bars C^3 C^3 are furnished. The distance between the said lugs or bosses is sufficient to permit a fall-back adjustment of the cam-bars C^3 C^3 with relation to the needle-actuating cams at each return movement of the parts.

Having reference now to the actuating devices for the yarn-carrier T , rods Y Y' , Figs.

1 and 5, which are fastened by their outer extremities to the cross-bar X , have connected with the inner extremities thereof the yarn-carrier actuating block Y . By means of the said block the yarn-carrier T is pushed across the needles in the movement of the cam-bars in one direction, through the engagement of the end of the block with an upturned lug or flange T' , Fig. 5, of the yarn-carrier. As the cam-bar returns in the opposite direction, the depending lip Y^3 of the draft-piece Y^2 upon block Y serves by its engagement with said lip or lug T' of the yarn-carrier to draw the yarn-carrier along. The space between the end of the push-block Y and the depending lip Y^3 of the draft-piece Y^2 is sufficient, as indicated by Figs. 1 and 5, to provide for a correct amount of lost-motion or play in the transmission of movement from block Y to the yarn-carrier to permit the yarn-carrier T to fall back at each stroke of the knitting-cams into proper adjustment with relation to the said cams.

The yarn-carrier T is provided with the loop v^3 , Figs. 1, 2 and 6, through which the body-yarn passes before reaching the usual distributing or delivery-eye of the carrier. For use in introducing a splice-yarn, a splice-yarn lever V , Figs. 1, 2, 5 and 6, is pivoted upon a vertical stud v with which the yarn-carrier T is provided. To the hub of the said lever V the splice-yarn guide V' is conveniently attached. See, more particularly, Figs. 1 and 6. A spring v' which is fastened to the lever V serves to hold the splice-yarn-guide V' in contact with the upper surface of the yarn-carrier T at the transverse slot t with which the yarn-carrier is formed, and operates to cause the said splice-yarn guide V' to follow the said surface as the lever V is swung upon its pivot. Inasmuch as the upper surface of yarn-carrier T dips downward from both sides to the delivery-eye, the guide V' in following the said surface has a compound horizontal and vertical swinging movement. The said transverse slot t extends from the delivery-eye of the yarn-carrier to one side of the latter, as indicated in Figs. 1, 5 and 6, and serves to permit the splice-yarn to be moved into and out of the delivery-eye, in placing the splice-yarn in and out of engagement with the needles, as the case may be. See the full and dotted lines in Fig. 6. For the purpose of operating the lever V to swing the latter and the splice-yarn-guide to move the splice-yarn into and out of position in the yarn-carrier for being engaged by the needles and knit, a trip-wire U is provided, it being connected, pivotally or otherwise, at u , Fig. 2, to the support U' , which latter is pivoted in turn at u' to the upright standard U^2 , see more particularly Fig. 2, fastened to the machine.

In operation, I prefer to start the knitting at the toe, in which case, the knitting is

begun in the usual manner. The body-yarn is threaded through the guide v^3 fastened on the yarn-carrier, before being led through the distributing-eye of the latter, the function of the guide v^3 being to prevent the body-yarn from being drawn out of the distributing-eye of the carrier through the slot t . The splice yarn is threaded through the guide v^2 of the splice-yarn-guide V' , and then through the distributing-eye of the yarn-carrier T . Both yarns are knit until the toe is completed. When splice-yarn is to be used only in the sole of the stocking, the trip U and its support U' are located in the position in which they are shown in Fig. 1, namely at the middle of the length of the needle-beds. When the knitting is being done on the row of needles nearer the operator and from the crank end, the travel of the yarn-carrier from right to left will cause the end of the splice-lever V to engage the trip-wire U . As a result of such engagement, the splice-lever will first move the trip-wire to the opposite side of the opening u^3 of the support U' , after which the resistance of said trip will be sufficient to swing the lever and with it the yarn-guide V' from the inoperative position shown in Fig. 1 into the knitting position shown in dotted lines 30 in Fig. 6. The trip then yields to allow the splice-lever to pass. The splice-yarn and body-yarn will be knit jointly to the left hand edge or turn of the fabric and will be returned on the opposite row of needles until lever V again comes in contact with the trip-wire, which will now bring the parts back into the position shown in Fig. 1, moving the splice-yarn outward along the slot t of the yarn-carrier. From this point the knitting will be continued with the body-yarn alone during the remainder of this course, and also during the return movement of the next course until the trip-wire again brings the splice-yarn into engagement with the needles as before described.

In practice, if necessary, any suitable take-up device will be employed to take up slack in the splice-yarn.

It should be noted that, when the splice-yarn lever is operated as above described at an intermediate point in the width of the tubular fabric that is being knit, the splice-yarn will be crossed from one side of the tubular fabric to the other. It will be obvious that this yarn must be severed in order to disconnect the two sides from each other before the goods can be finished. I provide as follows for effecting the severance upon the machine:—A knife W is pivoted upon the pin w between the rods Y , Y' . The said knife is held normally in its raised inoperative position, shown by full lines in Fig. 5, by a spring w^3 Fig. 1. Its cutting point w' is brought into the dotted line position in readiness for engagement with the portion of

splice-yarn which extends from one side of the tubular fabric to the other, through contact of the projection w^2 in the movement of the rods Y , yarn-carrier, etc., from right to left, (in Fig. 5) with the stop u^2 , which latter is fastened adjustably on the upper end of the support U' , the said projection w^2 passing underneath the stop u^2 in the continued movement of the part y . This cutting is preferably caused to occur near the end of the knitting stroke. In the return movement of the rods Y , Y' , yarn-carrier, etc., the rear extension w^4 of the knife, by its contact with the stop u^2 , brings the knife into its full-line position, Fig. 5, again, in which it is held by spring w^3 , or otherwise.

The downwardly inclined lip or piece t' , Fig. 5, fastened to the front end of the yarn-carrier engages with the yarn in the retracted position of the splice-yarn-guide, and assists in holding the splice-yarn out of contact with the needles when not being knit.

The toe and heel of a stocking may be knit with the splice-yarn and body yarn jointly, and while this is being done, trip-wire U and knife W should be rendered inoperative, which result is conveniently attained by raising the upper end of the support U' on its pivot U' , by hand or otherwise. The splice-yarn should be removed in knitting these parts when it is not needed, which is conveniently done by effecting a change of yarn-carriers.

Referring to Fig. 2 it is seen that the presser-hooks C held by the engagement of their heels by the walls of the cam-groove c^2 of cam-bar C^3 come too close together to admit of a knife passing between them to cut the splice yarn which is crossed from one row of needles to the other about midway of the fabric, whence recourse is had to a change of the cam groove, as c' in which the hooks are drawn further apart, see Figs. 1 and 4. Cam c is used to control the hooks in regular knitting.

I claim as my invention:

1. In a knitting machine, in combination, a yarn-carrier adapted to deliver two yarns to the needles, provided with a distributing-eye and with a transverse slot extending outward from the distributing-eye of the carrier beyond the reach of the needles, a guide controlling one of said yarns, and means for operating said guide in each stroke of the yarn-carrier whereby said yarn may be moved into the distributing-eye and knit during one portion of the course, and moved along said slot and thus removed from the reach of the needles during another portion of that course.

2. In a knitting machine, in combination, the yarn-carrier having a distributing eye and a slot leading transversely from the said distributing-eye beyond the reach of the needles, means for supplying a body-yarn continuously to the said distributing-eye, a mov-

able guide controlling a secondary yarn, and means to trip said movable guide in each stroke of the yarn-carrier into position to conduct the secondary yarn through the distributing eye to be knit with the body-yarn for a predetermined portion of a course in the knitting, and again move it to shift the secondary yarn into the said slot while the remainder of the course is being knit of the body-yarn alone.

3. In combination, two rows of knitting needles, needle-actuating cams, and means to operate said cams to effect tubular knitting, a yarn-carrier having a distributing-eye and means for supplying a body-yarn continuously to the said distributing-eye, a movable guide controlling a secondary yarn, and a trip acting to move said guide in each stroke of the yarn-carrier to place said secondary yarn in the distributing-eye at a predetermined point in the knitting in one direction to cause both yarns to be knitted together and to again move said guide at a point in the knitting in the opposite direction to remove the secondary yarn from the distributing-eye.

4. In a straight knitting machine, in combination, the reciprocating carrier provided with a distributing-eye and with a slot leading therefrom, a splice-lever provided with a guide for a splice-yarn, and a trip, as U, engaging with the said splice-lever in the movements of the yarn-carrier in both directions, and operating the same in the movement of the yarn-carrier in one direction to move the splice-yarn into the said distributing-eye to be knit by the needles, and acting in the movement of the yarn-carrier in the opposite direction to move the said splice-yarn through the said slot away from the distributing-eye out of reach of the needles.

5. The combination of a yarn-carrier provided with a slot t , a splice-lever V provided with a splice-yarn-guide given a movement having both vertical and horizontal components, and a yield trip whereby the splice-yarn may be engaged by the needles or

thrown out of engagement as described, substantially as specified.

6. The combination of a yarn-carrier provided with the slot t , the fixed guide v^3 , by which the main knitting yarn is confined to prevent it from accompanying the splice-yarn when the latter is thrown out of action the splice-yarn-guide t' , and a splice-yarn-controller, whereby the body-yarn may be knit and the splice-yarn knit jointly therewith or removed as desired, substantially as set forth.

7. The combination with opposite series of needles and devices for actuating the same, of a carrier for a knitting-yarn, means to supply a splice-yarn to the needles, controlling means to cross the splice-yarn from one series of needles to the other at an intermediate point in the width of a tubular fabric, and a cutter to sever the portion of splice-yarn extending from one side of the tubular fabric to the other.

8. The combination with opposite series of needles and devices for actuating the same, of a carrier for a knitting-yarn, splice-yarn feeding devices effecting a change of splice-yarn from one side of a tubular fabric to the other at an intermediate point in the width of the fabric, and a cutter traveling in unison with the carrier and operating to sever the portion of splice-yarn which extends from one side of said fabric to the other thereof.

9. The combination with the yarn-carrier, of the pivotally-mounted knife moving in unison with the yarn-carrier, and the stop by which the said knife is actuated.

10. The combination with the yarn-carrier, and the splice-yarn-guide, of the knife moving in unison with the yarn-carrier, and the operating devices for the splice-yarn-guide and knife.

In testimony whereof I affix my signature in presence of two witnesses.

WILLIAM WORTH BURSON.
